(57) CLAIM

The ornamental design for a vertical growing structure, as shown and described.

DESCRIPTION

FIG. 1 is a front perspective view of a vertical growing structure;
FIG. 2 is a right side elevation view thereof, the left side elevation view being a mirror image thereof;
FIG. 3 is a front elevation view thereof, the rear elevation view being a mirror image thereof;
FIG. 4 is a bottom plan view thereof; and,
FIG. 5 is a top plan view thereof.
